UNITED STATES PATENT OFFICE.

WILLIAM G. KENDALL, OF NEWARK, NEW JERSEY, ASSIGNOR TO PARFUMERIE RIGAUD, INC., OF NEW YORK, N. Y., A CORPORATION OF NEW YORK.

COMPACT HOLDER.

Application filed November 17, 1925, Serial No. 69,591. Renewed October 9, 1926.

This invention relates to improvements in compact holders, that is, metal holders for toilet powder compacts and has for its object the provision of a compact holder of the ordinary form and size which will be capable of holding three separate cakes or compacts of toilet powder in a reasonable compass. For this purpose I have devised a novel bifurcated tray for holding two cakes of compact powder on one side of the compact holder.

Further objects of the invention will be apparent from the drawings in which—

Figure 1 is a perspective view of the entire holder and accompanying powder puff showing my improved tray in position.

Figure 2 is a sectional view along the line 2—2 of Figure 1.

Figure 3 is a plan view of the improved tray which is the particular object of this invention.

Figure 4 is a side elevation of said tray.

Figure 5 is a side elevation of said tray in folded position.

Figure 6 is a perspective view of the three elements constituting my improved tray.

A and B are the conventional hollow members forming the body of the usual compact and joined by a hinge of ordinary construction, C. Within the members A and B are held a toilet powder compact D of the usual form and in the tray E fully shown in Figures 3 and 6, two separate semi-circular discs of toilet compact powder can be placed, though for convenience, the tray in this drawing is shown empty. The tray E is formed of the elements F and F', each element having a perpendicular flange at right angles to the body of the tray, H and H'. The flanges H and H' have integrally formed thereon hinged forming members and with the mirror K are joined together by a pintle M. Preferably, the flanges H and H' are formed integrally from the same sheet of metal as F and F', the flanges H and H' serving as separators for the discs of toilet

powder placed in the halves F and F'. When desired, the halves of the tray may be folded upon each other as shown in Figure 5.

It is also apparent that a tray of this construction can be substituted in the other half of the compact holder where the toilet compact D is shown, so with the compact holder having this improved tray construction, it would be possible to have four different cakes or compacts of toilet powder or rouge in a compact holder of ordinary size. The tray E is held within the member A by means of depressions R shown in Figure 1 and the tray E may be removed by pressure upon the member A.

I do not, however, herein claim any novelty in this form of holding the tray E within the compact holder; the novelty herein consisting in the form of holder for a toilet powder compact as shown in detail in Figures 3, 4, 5 and 6.

Having fully described my invention, what I claim is:

1. In a compact holder, a compact holding tray divided by a hinge in the center thereof, so that the halves of said tray are foldable upon each other, each half of said tray being adapted to hold a semi-circular compact of a cosmetic in solid form.

2. In a compact holder, a circular tray divided in the center thereof, a flange on each half of said tray at right angles thereto, the top of said flanges being connected by a hinge so that the halves of said tray are foldable upon each other.

3. In a compact holder, a tray divided in halves, a flange on each half at right angles thereto and integral therewith, said flanges being connected to each other by a hinge.

4. In a compact holder, a tray divided in halves, said halves being connected and foldable upon each other by a hinge, and retaining means on each half adapted to hold a powder compact.

In testimony whereof I affix my signature.
WILLIAM G. KENDALL.
